METHOD OF MAKING DOUBLE BELTS

Original Filed Feb. 1, 1927

UNITED STATES PATENT OFFICE

WINFRED S. GRIFFITH, OF WORCESTER, MASSACHUSETTS, ASSIGNOR TO GRATON & KNIGHT COMPANY, OF WORCESTER, MASSACHUSETTS, A CORPORATION OF MASSACHUSETTS

METHOD OF MAKING DOUBLE BELTS

Application filed February 1, 1927, Serial No. 165,215. Renewed November 6, 1931.

This invention relates to the manufacture of double belts and more particularly to the manufacture of double leather belts from two single plies or layers of leather.

5 It is the general object of my invention to provide a method of manufacture by which a multi-ply belt may be produced in a continuous operation. A further object is to provide a method of manufacture by 10 which a plurality of single layers of belt material may be secured together under tension by virtue of cellulose cementing material. A still further object of the invention is to introduce a cellulose material between the assembled layers in the form of a continuous strip of uniform thickness.

The details of my improved method will be hereinafter described with reference to the illustrative drawing, and will be more 20 fully set forth in the appended claims. In the drawing, I have shown one form of machine by which my improved method may be carried out.

Fig. 1 is a side elevation, partly in section, 25 of the head or cementing end of a machine adapted for the carrying out of my improved method; and

Fig. 2 is a similar view of the pressing and winding portion of the machine, (Fig. 2 being 30 a continuation of Fig. 1 at the right hand end thereof).

Referring to the drawing, I have indicated, more or less diagrammatically, a machine in which two single-ply belt layers B 35 and B' are supplied from rolls R and R', rotatably mounted on fixed stands 10 and 11.

Any suitable means is provided for applying friction to the belt layers B and B', and they are indicated in the drawing as being 40 tensioned or retarded by ropes 12, passing over and wound around the axles of the rolls R and R', and having weights 13 attached to the depending free ends of the ropes.

The friction may be varied by increasing 45 or decreasing the size of the weights 13, or by taking off or adding turns to the rope on the axles of the rolls. The relative tension on the belt layers B and B' may thus be conveniently adjusted.

50 The upper layer B passes around an upper

guide roll 15 and between a pair of rolls 16, which may be adjusted toward and from each other to apply additional tension to the belt layer B if so desired. The layer B then passes over another guide roll 17 and then downward along side a plate or table 18 to a lower guide roll 19.

The lower belt layer B' passes between tension rollers 20, adjustable toward and from each other in the same way as the rollers 16, and then passes upward over an inclined 55 apron 21 to a point adjacent the guide roll 19 previously described.

A strip S of celluloid is drawn from a roll 22 rotatably mounted in fixed bearings and preferably provided with a device for applying limited tension thereto. In the drawing, I have shown a rope or strap 23 resting on the roll 22 and drawn downward 60 by a small weight 24.

The celluloid strip S passes downward into a tank 25 containing a solution adapted to soften the celluloid as the strip S is drawn therethrough. The strip is guided through the solution by guide rods 26 and 27 which cause the strip S to be submerged in the solution.

The moistened strip is delivered between the belt layers B and B' adjacent the guide roll 19 and the three strips of material are drawn forward between a series of presser and tension rolls, by which the several layers are caused to firmly adhere to each other. Preferably these rolls comprise successive 80 pairs of semipositive tension rolls 30 and 31, one roll of each pair, as 30, being positively rotated, while the other roll is free 85 to turn.

Each roll 30 is preferably a metal surfaced 90 roll, while each roll 31 is preferably covered with rubber or other similar material.

Between the pairs of tension rolls, the assembled belt passes through a series of idle presser rolls 33 and 34, the rolls 33 rotating in fixed bearings and the rolls 34 being freely movable vertically, and both sets of rolls being freely rotatable.

The several driven rolls 30 are simultaneously rotated in some convenient manner, as 95 by a worm shaft 36 having worms 37 each 100

engaging a worm wheel 38 associated with one of the rolls 30.

At the extreme end of the series of tension and presser rolls, I have provided a pair of 5 positively driven tension rolls 40 and 41 (Fig. 2). These rolls are preferably leather faced and the roll 40 is driven from the shaft 36 by a worm 37 and worm wheel 38 as previously described. The roll 41 is geared directly to 10 the roll 40 and is positively rotated thereby.

The belt is thus under tension all the time from a point prior to the cementing operation until it passes the positively driven rolls 40 and 41. During this time rolling 15 pressure is repeatedly applied thereto by the semi-positive tension rolls 30 and 31 and by the idle presser rolls 33 and 34.

After passing the rolls 40 and 41, the belt is drawn under one or more edge-pressing 20 devices, in each of which a series of narrow rolls 45 are yieldingly mounted upon spring-pressed bearing members 46 and engage the edges of the belt as it is drawn thereunder, a separate series of rolls 45 being provided for 25 each edge of the belt.

After passing under the edge pressing rolls 45, the belt is drawn over a table 50, which may be of any desired length to permit the cement to firmly set before the belt is wound 30 up on the drum 51, which preferably has a friction connection to a gear 52 which is rotated from a worm shaft 53 positively connected for operation in conjunction with the worm shaft 36, previously described.

35 Any suitable driving mechanism may be provided for rotating the worm shafts, and the gear 52 is preferably rotated at such speed that it will always exert a frictional drag or pull upon the drum 51, thus placing additional tension upon the belt after it passes 40 the positive tension rolls 40 and 41. This drag or pull upon the belt causes it to be wound tightly on the drum, and each additional layer exerts substantial pressure upon 45 the belt layers therebeneath previously wound on the drum.

Guide plates 54 are provided for keeping the belt properly aligned during the winding upon the drum. These guide plates 54 50 may be swung upward about a pivot 55 whenever it is desired to remove a roll of belting from the drum 51.

Having thus described my invention, it will be seen that I have provided a method 55 of operation by which double or two-ply belting may be manufactured as a continuous operation, and furthermore that I have provided a method by which water-proof belting may be manufactured as a continuous 60 operation and with the use of softened celluloid as the cementing material.

The matter of joining the layers together under tension has been found to be of very great practical importance as regards stretch- 65 ing. A belt cemented under tension is less

subject to stretch than a belt cemented without tension.

In the manufacture of high grade two-ply leather belting, it is desirable to preserve the full thickness of the hide in each layer 70 and as this thickness varies substantially in different skins, it is necessary to match the two layers as they are built up, so that at each point in the belt the combined thickness of the two layers may be kept substantially 75 uniform. It is customary to place marks on the layers at frequent intervals as they are matched up, and by slightly varying the tension on the layers the operator of my improved machine is able to keep these marks 80 together as the layers are cemented, thus producing a substantially uniform belt thickness from hides varying considerably in thickness.

While I have described a diagrammatic 85 form of machine adapted to carry out my improved method of process the method is not dependent upon the use of a particular machine and may be carried out in other machines or manually if so desired. It is essential, however, in order to obtain the best results, that the belt layers be under substantial tension during the cementing operation, and that pressure be promptly applied to the belt after the cementing material is inserted 90 between the layers and while the belt is still under tension.

While I have described the use of softened celluloid as the cementing material, many 95 of the advantages of my invention may be attained with other forms of cementing material.

Having thus described my improved method and an illustrative machine for practicing the same, I do not wish to be limited to the details of the machine or otherwise, except as set forth in the claims, but what I claim is:—

1. The method of making double belt 110 which consists in tensioning two single-ply belt layers, providing cementing material for the tensioned belt layers, assembling said layers and thereafter applying pressure to the assembled and cemented belt layers beyond the point of assembling and while still under tension.

2. The method of making double belt 115 which consists in tensioning two single-ply belt layers, providing cementing material for the tensioned belt layers, assembling said layers and thereafter applying pressure to the assembled and cemented belt layers beyond the point of assembling and while still under tension and as a continuous operation.

3. The method of making double belt 125 which consists in tensioning two single-ply belt layers, providing cementing material for the tensioned belt layers, assembling said layers and material applying additional positive tension to the assembled and cement- 130

- ed belt at a point beyond and remote from the point of assembling, and applying yielding pressure to said belt at a plurality of points intermediate the points of assembling and of applying positive tension thereto. 70
4. The method of making double belt which consists in tensioning two single-ply belt layers, providing cementing material for the tensioned belt layers, assembling said layers and material, applying pressure to the assembled and cemented belt while still under tension, and applying additional pressure to the edge portions only of the assembled belt. 75
5. The method of making double belt which consists in tensioning two single-ply belt layers, providing cementing material for the tensioned belt layers, assembling said layers and material, applying pressure to the assembled and cemented belt while still under tension, and varying the relative tension upon the two single-ply belt layers to control the relative feed of said belt layers. 80
6. The method of making double belts which consists in tensioning two single-ply belt layers, feeding a cementing strip between the tensioned belt layers, assembling said layers and strip and thereafter applying pressure to the assembled and cemented belt layers beyond the point of assembling and while still under tension. 85
7. The method of making double belts which consists in tensioning two single-ply belt layers, feeding a strip of softened cellulose material under tension between said tensioned belt layers, assembling said layers and strip and thereafter applying pressure to the assembled and cemented belt layers beyond the point of assembling and while still under tension and as a continuous operation. 90
- 40 8. The method of making waterproof double belt which consists in tensioning two single-ply belt layers, softening a strip of cellulose material by the action of a solvent and inserting same after the softening between the tensioned belt layers, assembling said layers and strip and applying pressure to the assembled belt layers and cellulose material beyond the point of assembling and while still under tension, all as a continuous operation. 100
- 45 9. The method of making water proof double belt which consists in tensioning two single-ply belt layers, softening a continuous strip of cellulose material by the action of a solvent and inserting same between the tensioned belt layers, assembling said layers and strip and applying continuous rolling pressure to the assembled belt layers and cellulose material beyond the point of assembling and while still under tension. 105
- 50 10. The method of making double belts which consists in tensioning two single-ply belt layers, inserting a cementing material between the tensioned belt layers and assembling the layers at the point of insertion of the cementing material, thereafter applying 110
- a rolling pressure to the assembled belt at points beyond the point of assembling and applying additional pressure and additional tension to said belt beyond the points of application of rolling pressure. 115
- 55 11. The method of making double belts which consists in tensioning two single-ply belt layers, inserting a cementing material between the tensioned belt layers and assembling the layers at the point of insertion of the cementing material, thereafter applying a rolling pressure to the assembled belt at points beyond the point of assembling, and applying additional pressure to the edge portions only of the assembled belt. 120
- 60 12. The method of making double belts which consists in tensioning two single-ply belt layers, inserting a cementing material between the tensioned belt layers and assembling the layers at the point of insertion of the cementing material, and thereafter applying a semi-positive tension followed by a rolling pressure to said assembled belt beyond the point of assembling. 125
- 65 13. The method of making waterproof double belts which consists in tensioning two single-ply belt layers, inserting and assembling therebetween a layer of cellulose cementing material, and applying pressure to the assembled belt layers and cementing material beyond the point of assembly and while still under tension, all as a continuous operation. 130
14. The method of making waterproof double belts which consists in tensioning two single-ply belt layers, inserting and assembling therebetween a continuous layer of cellulose cementing material, and applying continuous rolling pressure to the assembled belt layers and cementing material beyond the point of assembly and while still under tension. 135
